LAMP STARTING DEVICE

Hans M. Erdmann, New York, N. Y., assignor to
Ne-Arga Corporation, New York, N. Y., a cor-
poration of New York

Application January 18, 1930, Serial No. 421,679

2 Claims. (CL. 176—45)

This invention relates to starting devices for mercury arc lamps and similar apparatus.

It is an object of my invention to provide a starting means for mercury arc lamps or similar electrical discharge devices, which is so arranged as to start operation of the lamp and then remain inoperative until it is intentionally made operative again.

In the production of talking moving pictures it is important to have, as nearly as possible, a complete absence of all unnecessary noises and electrical disturbances. Mercury arc lamps equipped with starting devices of the type known heretofore are unsuitable for use in the production of talking pictures because when one of the lamps becomes extinguished, the starting device thereof immediately starts to function so as to reignite the lamp, thereby producing a clicking noise. The noise produced by the ordinary starting device is sufficient to cause a serious disturbance, which will be made part of the sound record. Likewise, when the starting device serves to create a momentary high potential starting current, this starting current causes a disturbance in the recording of the sound if an electrical process is being used. This recording is usually carried out by electrical recording apparatus, including a high power amplifier which serves to amplify the sound currents picked up through microphones. These amplifiers are sufficiently powerful to pick up the disturbing electrical waves as well, thereby impressing on the recording medium an undesired noise.

In accordance with my invention I provide means responsive to the initiation of operation of the lamp to render inactive the starting mechanism thereof so that if the lamp later becomes extinguished, the starting device will be unable to function. The lamp will therefore remain unlit until it is manually restored to operation at an opportune moment. I accomplish this result by providing relay means which serves to open the energizing circuit of the starting device upon the creation of a self-sustained discharge through the tube.

The objects and advantages of my invention and the manner of attaining them will be made clear in the following description and accompanying drawing.

In the drawing, reference numeral 1 indicates a mercury arc tube or similar electrical discharge device requiring a high starting potential, which is adapted to be energized from a source of power 2 through conductors 3 and 4. Placed in series with the tube 1 is an inductance coil 5 and a

control switch 6. When the switch 6 is closed, current passes from a source 2 through a conductor 7, contacts 8 of a mercury switch 9, ballast resistance 10, contacts 11 of a mercury switch 12, and inductance 5, back to the other side of the line. This current causes the core 13 of the inductance to be energized, thereby attracting to the core armature 14. This movement of the armature tilts the mercury switch 12, thereby breaking the circuit between contacts 11. This breakage of the circuit causes a surge of potential to be generated by the inductance 5, which surge passes to the tube 1, thereby ionizing the gas therein or vaporizing the mercury and initiating a discharge therethrough.

Immediately after the closure of the control switch 6 the current also passes through the conductor 7, a magnet coil 15, and ballast resistance 16, back to the other side of the line, thereby causing magnetization of core 17 of the magnet. This magnetization causes the armature 18 to be attracted to the core, whereby the contacts 8 of switch 9 are broken and further operation of the starting mechanism of the lamp is prevented.

In order that the breakage of the contacts 8 will not occur too rapidly a dashpot 19 is furnished, which permits the armature 18 to move towards core 17 slowly. This dashpot may be of any well-known type and may be provided with the usual form of regulator, so that the time during which the contacts 8 remain closed after the closure of the control switch 6, may be regulated to allow a sufficient operating interval for the starting mechanism to create a discharge through the tube 1.

While I have shown mercury type switches at 9 and 12, it will be understood that any other type may be used if desired, it merely being necessary that the contacts 8 and 11 be broken upon sufficient tilting of the armatures 18 and 14, respectively. The function of the resistances 10 and 16 is to limit the current through their respective circuits, to the desired value. Condenser 19 serves to prevent arcing at contacts 11 and thereby increase the potential generated by inductance 5. A similar condenser 20 may be connected across contacts 8 to prevent arcing thereof.

While but a single lamp is shown in the drawing several lamps might be controlled by a single time controlled switch 9. In this case each of the several starting mechanisms would be so connected as to have its operating circuit broken by switch 9.

It will be obvious to those skilled in the art that the invention is capable of a wide variety of mod-

ifications and adaptations and that the present disclosure is intended merely to illustrate its nature without limiting its scope, which is defined in the claims.

5 What is claimed is:

- 5 1. In a lighting circuit, a lamp, a power source therefor, a switch for said power source, a starting device for said lamp, and mechanical time controlled means for rendering said starting device inoperative after the expiration of a short time interval from the closing of the switch of the power source and maintaining said starting device inoperative while said switch from said power source is closed, whether said lamp is operating or not operating, said starting device being again operable only upon the disconnection and reconnection of the lamp with said source of power.
- 10 2. In a lighting circuit, a lamp, a power source therefor, a switch for said power source, a starting device for said lamp, and mechanical time controlled means for rendering said starting device inoperative after the expiration of a short time interval from the closing of the switch of the power source, said mechanical time controlled means being operated by a coil connected in parallel with said power source and maintaining said starting device inoperative while said switch from said power source is closed, whether said lamp is operating or not operating, said starting device being again operable only upon the disconnection and reconnection of the lamp with said source of power.
